ABSTRACT

A lighting assembly comprising a housing (2), a lighting system and a reflector system. The housing (2) has a longitudinal direction, a lateral direction and a height direction which are perpendicular to each other. The lighting system is installed in the housing (2) and configured to produce light and emit the light out from the housing (2), the lighting system comprising a first light source (61). The reflector system is configured for reflecting the light produced by the lighting system out from the housing (2) and comprises a first reflector (41) including a first reflector surface (411) which is a concave surface with a first radius of curvature (r1). The first reflector (41) is also provided with a second reflector surface (412) which is a concave surface with a second radius of curvature (r2) which is larger than the first radius of curvature (r1), a centre of curvature (cc2) of the second reflector surface (412) being spaced from a centre of curvature (cc1) of the first reflector surface (411). The lighting assembly is configured to be such that most of the light emitted by the lighting system out from the housing (2) passes via the reflector system.

LIGHTING ASSEMBLY

This application claims benefit of Serial No. 20185079, filed 30 Jan. 2018 in Finland, and which application is incorporated herein by reference. To the extent appropriate, a claim of priority is made to the above disclosed application.

BACKGROUND OF THE INVENTION

The invention relates to a lighting assembly which comprises a lighting system installed in a housing and configured to produce light and emit the light out from the housing, and a reflector system configured for reflecting the light produced by the lighting system out from the housing.

It is known to produce a narrow light beam with a lighting assembly by using a suitable lens element. The known lens elements configured for producing a narrow light beam are relatively expensive.

SHORT DESCRIPTION OF THE INVENTION

The object of the invention is to provide a lighting assembly producing a narrow light beam without the known type of lens element.

The invention is based on the idea of providing the lighting assembly with a reflector having two concave surfaces, each having a different radius of curvature and being configured for producing a narrow light beam. The lighting assembly is configured to be such that most of the light emitted by the light source out from the housing passes via the reflector provided with the concave surfaces.

The advantage of the lighting assembly according to the invention is its simplicity and low manufacturing costs.

SHORT DESCRIPTION OF THE FIGURES

The invention will now be described in detail in the context of preferred embodiments, with reference to the accompanying drawings in which:

FIG. 1 shows a lighting assembly according to one embodiment of the invention;

FIG. 2 shows a cross-section of the lighting assembly of FIG. 1; and

FIG. 3 illustrates the geometry of the lighting system and the reflector system in the lighting assembly of FIG. 1.

DETAILED DESCRIPTION OF THE INVENTION

FIG. 1 shows a lighting assembly which comprises a housing 2, a lighting system, a reflector system, a fin system, and a protection element 10. The housing 2 has a longitudinal direction, a lateral direction and a height direction which are perpendicular to each other. The longitudinal dimension of the housing 2 is greater than its lateral or height dimension.

FIG. 2 shows a cross-section of the lighting assembly of FIG. 1. In FIG. 2 the longitudinal direction is perpendicular to the image plane. The geometrical features of the lighting assembly, such as various angles, are indicated in FIG. 3 only.

The lighting system is installed in the housing 2 and configured to produce light and emit the light out from the housing 2. The lighting system comprises a first light source 61 and a second light source 62.

2

The reflector system is configured for reflecting the light produced by the lighting system out from the housing 2 with a desired shape of light beam, without a separate lens element. The reflector system comprises a first reflector 41 and a second reflector 42 which are separated by a black and matt-surfaced antireflection surface 45.

The lighting assembly is configured to be such that substantially all of the light emitted by the lighting system out from the housing 2 passes via the reflector system. In this context, substantially all refers to a proportion of 95% or greater. In one alternative embodiment the lighting assembly is configured to be such that most of the light emitted by the lighting system out from the housing passes via the reflector system.

15 The fin system is configured to reduce lateral reflection of the light output from the lighting assembly. The fin system comprises six longitudinally extending fins denoted by 81-86. Each of the fins 81-86 is substantially an opaque and weakly reflective element located on the path of the ray of light output from the lighting system after the reflector system. Fins 81-83 are configured to reduce the lateral reflection of the light output from the second light source 62, and fins 84-86 are configured to reduce the lateral reflection of the light output from the first light source 61. The fins 81-86 are dark-painted aluminium elements.

20 In alternative embodiments the number of fins in the fin system is 4-8. The number of fins depends on the width of the lighting fixture, such that a fin system of a wide lighting fixture comprises more fins than that of a narrow lighting fixture.

25 The protection element 10 is translucent material and configured to protect the lighting system and the reflector system. The protection element 10 comprises a flat plate arranged perpendicular to the height direction. In one alternative embodiment the protection element is manufactured by co-extrusion, and the fin system is integrated with the protection element, such that the protection element is manufactured from translucent material and the fins are manufactured from opaque and weakly reflective material.

30 As seen in FIG. 2, the lighting assembly is symmetrical relative to a plane of symmetry ps. The longitudinal and height directions are parallel to the plane of symmetry ps, and the lateral direction is perpendicular to the plane of symmetry. The second light source 62 is geometrically a mirror image of the first light source 61 relative to the plane of symmetry ps. The second reflector 42 is geometrically a mirror image of the first reflector 41 relative to the plane of symmetry ps. In one alternative embodiment the lighting assembly only comprises the elements on the right side of the plane of symmetry ps of FIG. 2, i.e. the lighting assembly only comprises the first light source and the first reflector.

35 The first reflector 41 includes a first reflector surface 411 and a second reflector surface 412. The first reflector surface 411 is a concave surface with a first radius of curvature r1. The first radius of curvature r1 is substantially larger than the distance of the first light source 61 from the first reflector surface 411. Accordingly, the first radius of curvature r1 is also substantially larger than the distance of the centre of the first light source 61 from any point of the first reflector surface 411 as viewed in a plane perpendicular to the longitudinal direction.

40 The second reflector surface 412 is a concave surface with a second radius of curvature r2 which is larger than the first radius of curvature r1. A centre of curvature cc2 of the second reflector surface 412 is spaced from a centre of curvature cc1 of the first reflector surface 411. The second

radius of curvature r_2 is substantially larger than the distance of the first light source **61** from the second reflector surface **412**.

The first radius of curvature r_1 of the first reflector surface **411** is over 300% larger than the circumferential dimension of the first reflector surface **411**, i.e. the distance from a first edge of the first reflector surface **411** to its second edge along the reflector surface. The second radius of curvature r_2 of the second reflector surface **412** is over 400% larger than the circumferential dimension of the second reflector surface **412**. The circumferential dimension of the second reflector surface **412** is larger than the circumferential dimension of the first reflector surface **411**. In one alternative embodiment the first radius of curvature of the first reflector surface is over 100% larger than the circumferential dimension of the first reflector surface, and the second radius of curvature of the second reflector surface is over 150% larger than the circumferential dimension of the second reflector surface.

The first reflector surface **411** and the second reflector surface **412** are adjacent reflector surfaces. As viewed in the lateral direction, the first reflector surface **411** and the second reflector surface **412** are located on the same side of the first light source **61**. The second reflector surface **412** is located in the lateral direction further away from the first light source **61** than the first reflector surface **411**. The reflector comprising the first reflector **41** and the second reflector **42** in the reflector system is a solid element which is manufactured from one blank sheet material by bending. In an alternative embodiment the first reflector **41** is a solid element which is manufactured from one blank sheet material by bending.

A principal axis pa_1 of the first reflector surface **411** is angled at a first principal axis angle α_1 relative to the height direction, and a principal axis pa_2 of the second reflector surface **412** is angled at a second principal axis angle α_2 relative to the height direction. Both of the principal axis pa_1 of the first reflector surface **411** and the principal axis pa_2 of the second reflector surface **412** are inclined towards the first light source **61** with respect to the height direction. The first principal axis angle α_1 is approximately 25° , and the second principal axis angle α_2 is approximately 40° . In one alternative embodiment the first principal axis angle is 15° - 35° , and the second principal axis angle is 30° - 50° , such that the second principal axis angle is at least 10° larger than the first principal axis angle.

The first reflector surface **411** and the second reflector surface **412** of the first reflector **41** are located, with respect to the first light source **61**, such that a ray of light output from the centre of the first light source **61** is reflected from a first edge of the first reflector surface **411** at a first reflection angle β_1 relative to the height direction, from a second edge of the first reflector surface **411** at a second reflection angle β_2 relative to the height direction, from the middle point between a first edge and a second edge of the second reflector surface **412** at a third reflection angle β_{31} relative to the height direction, and from the second edge of the second reflector surface **412** at a fourth reflection angle β_4 relative to the height direction. The entire surface configured for reflecting light in the first reflector **41** is located between the first edge of the first reflector surface **411** and the second edge of the second reflector surface **412**.

The first edge of each of the reflector surfaces **411** and **412** is located, in the lateral direction, closer to the first light source **61** than the second edge. The first edge and the second edge of each of the reflector surfaces **411** and **412** extend parallel to the longitudinal direction.

The first reflection angle β_1 is approximately 0° , the second reflection angle β_2 is directed approximately 3° outward, the third reflection angle β_{31} and the fourth reflection angle β_4 are directed approximately 3° inward, the outward angle being directed away from the first light source **61**, and the inward angle being directed toward the first light source **61**.

The second edge of the first reflector surface **411** substantially coincides with the first edge of the second reflector surface **412**, i.e. they are spaced by less than 3 mm. The small distance between the second edge of the first reflector surface **411** and the first edge of the second reflector surface **412** ensures that the smallest possible amount of light output from the first light source **61** falling on the boundary between the first reflector surface **411** and the second reflector surface **412** is absorbed or reflected in a wrong direction.

The small values of the reflection angles β_1 , β_2 , β_{31} and β_4 produce a narrow light beam for the lighting assembly. In one alternative embodiment each of the first reflection angle, the second reflection angle, the third reflection angle and the fourth reflection angle is smaller than a threshold angle of reflection which is 0° - 10° . In another alternative embodiment each of the first reflection angle, the second reflection angle, the third reflection angle and the fourth reflection angle is smaller than a threshold angle of reflection which is 0° - 25° .

The first reflector **41** of the lighting assembly shown in FIG. 2 comprises exactly two concave reflector surfaces, i.e. the first reflector surface **411** and the second reflector surface **412**. In alternative embodiments the first reflector may comprise three or more concave reflector surfaces.

The lighting system comprises a circuit board **612**, and the first light source **61** comprises several LEDs **615** installed on the circuit board **612**. The several LEDs **615** are installed in a row parallel to the longitudinal direction. The several LEDs **615** are white LEDs. In one alternative embodiment the first light source comprises coloured LEDs. In another alternative embodiment the first light source comprises both white and coloured LEDs.

The circuit board **612** defines a plane which is angled at a circuit board angle γ relative to the height direction. The circuit board angle γ is approximately 30° . The principal axis pa_1 of the first reflector surface and the principal axis pa_2 of the second reflector surface pass through the circuit board **612**. The rays of light output from the centre of the first light source **61**, which are reflected from the first edge of the first reflector surface **411**, the second edge of the first reflector surface **411**, the first edge of the second reflector surface **412**, and the second edge of the second reflector surface **412**, each bypass the circuit board **612** without touching it. In one alternative embodiment the circuit board angle is 20° - 45° , and the principal axis of the first reflector surface passes through the circuit board.

It is obvious for a person skilled in the art that the basic idea of the invention may be implemented in many different ways. The invention and its embodiments are thus not limited to the above-described examples but may vary within the scope of the claims.

The invention claimed is:

1. A lighting assembly, wherein:
the lighting assembly comprises a housing having a longitudinal direction, a lateral direction and a height direction which are perpendicular to each other;
the lighting assembly comprises a lighting system which is installed in the housing and configured to produce

light and emit the light out from the housing, the lighting system comprising a first light source; the lighting assembly comprises a reflector system which is configured for reflecting the light produced by the lighting system out from the housing and comprises a first reflector including a first reflector surface which is a concave surface with a first radius of curvature, and a second reflector surface which is a concave surface with a second radius of curvature which is larger than the first radius of curvature, a center of curvature of the second reflector surface being spaced from a center of curvature of the first reflector surface;

the lighting assembly is configured to direct most of the light emitted by the lighting system out from the housing passes via the reflector system;

the first reflector surface and the second reflector surface are adjacent reflector surfaces, of which the second reflector surface is located in the lateral direction further away from the first light source than the first reflector surface; and

the first reflector surface and the second reflector surface of the first reflector are located, with respect to the first light source, such that a ray of light output from the center of the first light source is reflected from a first edge of the first reflector surface at a first reflection angle relative to the height direction, from a second edge of the first reflector surface at a second reflection angle relative to the height direction, from the middle point between a first edge and a second edge of the second reflector surface at a third reflection angle relative to the height direction, and from the second edge of the second reflector surface at a fourth reflection angle relative to the height direction, wherein each of the first reflection angle, the second reflection angle, the third reflection angle and the fourth reflection angle is smaller than a threshold angle of reflection which is 0°-10°.

2. The lighting assembly according to claim 1, wherein a principal axis of the first reflector surface is angled at a first

principal axis angle relative to the height direction, and a principal axis of the second reflector surface is angled at a second principal axis angle relative to the height direction, both of the principal axis of the first reflector surface and the principle axis of the second reflector surface being inclined towards the first light source with respect to the height direction.

3. The lighting assembly according to claim 2, wherein the first principal axis angle is 15°-35°, and the second principal axis angle is 30°-50°.

4. The lighting assembly according to claim 2, wherein the second principal axis angle is at least 10° larger than the first principal axis angle.

5. The lighting assembly according to claim 1, wherein the first radius of curvature is larger than the distance of the first light source from the first reflector surface.

6. The lighting assembly according to claim 1, wherein the lighting system comprises a circuit board, and the first light source comprises several LEDs installed on the circuit board, the circuit board being located such that a plane defined by the circuit board is angled at a circuit board angle relative to the height direction, the circuit board angle being 20°-45°, and the principal axis of the first reflector surface passes through the circuit board.

7. The lighting assembly according to claim 1, wherein the lighting assembly comprises a fin system which is configured to reduce lateral reflection of the light output from the lighting assembly, the fin system comprising several longitudinally extending fins which are each opaque and weakly reflective elements located on the path of the ray of light output from the lighting system after the reflector system.

8. The lighting assembly according to claim 1, wherein the lighting assembly is configured to be such that substantially all of the light emitted by the lighting system out from the housing passes via the reflector system.
